CLAIM

I claim the ornamental design for a rotating advertisement stand, as shown and described.

DESCRIPTION

FIG. 1 is a front elevation view of the rotating advertisement stand showing my novel design;

FIG. 2 is a rear elevation view thereof;

FIG. 3 is a left elevation view thereof;

FIG. 4 is a right elevation view thereof;

FIG. 5 is a top plan view thereof; and,

FIG. 6 is a bottom plan view thereof.

The broken lines showing in all figures are for illustrative purposes only and form no part of the claimed design.

The break lines in the cord indicate no specific length.
